UNITED STATES PATENT OFFICE.

JOHN VAN RADEN AND NORMAN VAN RADEN, OF MELVIN, MINNESOTA.

SKATE-SHARPENER.

1,195,880.

Specification of Letters Patent. Patented Aug. 22, 1916.

Application filed April 3, 1916. Serial No. 88,497.

To all whom it may concern:

Be it known that we, JOHN VAN RADEN and NORMAN VAN RADEN, both citizens of the United States, residing at Melvin, in the county of Polk, State of Minnesota, have invented a new and useful Skate-Sharpener; and we do hereby declare the following to be a full, clear, and exact description of the invention, such as will enable others skilled in the art to which it appertains to make and use the same.

The present invention relates to a skate sharpener, and has for its object to provide a device of this character which can be conveniently carried in the pocket and which embodies novel features of construction whereby the skate can be easily and quickly sharpened in a most effective manner.

Further objects of the invention are to provide a device of this character which is comparatively simple and inexpensive in its construction, which locks the sharpening file rigidly in position when the device is in use, which admits of the file being readily adjusted or replaced, and which can be used both as a key for the skates and as a file for sharpening the same.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a perspective view of a combination skate key and sharpener constructed in accordance with the invention. Fig. 2 is a side elevation of the same, portions being broken away and shown in section to illustrate more clearly the details of construction. Fig. 3 is an end view, portions being broken away and shown in section. Fig. 4 is a side elevation of a slightly modified form of the invention, portions being broken away and shown in section, and the sharpening file being removed.

Corresponding and like parts are referred to in the following description and indicated in all the views of the drawing by the same reference characters.

Specifically describing the present embodiment of the invention, the numeral 1 designates a stem which has a polygonal

socket 2 in one end thereof, and is provided at its opposite end with a T shaped head 3. Integral rivet members 4 project upwardly from opposite sides of the head 3, and engage the base of an elongated sheet metal jacket 5, said jacket being open at the top and one end thereof, and the sides 5^a thereof having a stiff spring action for the purpose of engaging the sheet metal file receiving clip 6, and causing the latter to securely grip the file 7. One end of the jacket 5 is partially closed by a tongue 5^b which terminates short of the ends of the sides 5^a.

The file 7 is preferably substantially square in cross section, having four operating faces which can be successively brought into operative position as they become worn by use. The clip 6 is formed of thin sheet metal and is open at the top and both ends. The sides 6^a are contracted or deflected inwardly toward each other above the file, thereby holding the file in position in the base of the clip, and providing a guide for directing the file in its back and forth movements across the skate. When the clip 6 is forced in position within the jacket 5, the spring sides 5^a of the jacket forcibly engage the clip so as to cause it to securely grip the file. The tongue 5^b engages one end of the clip 6, and the clip and file are securely gripped so that the stem 1 can be used as a handle in manipulating the file.

A slight modification is shown by Fig. 4, in which the base of the tongue 5^b is shown as formed with a small crimp 8 to fit over and frictionally engage the end of the clip 6. The opposite end of the clip 6 is shown as having a small spring tongue 9 stamped therefrom for engagement with the end of the jacket 5. Such a construction would admit of the two members being securely locked together, and might be desirable under some circumstances.

The polygonal socket 2 at the end of the stem of the T-shaped stock enables the device to be used as a skate key, so that the tool can be conveniently used either as a key for adjusting the skates, or as a sharpening device.

Having thus described the invention, what we claim as new and desire to secure by Letters Patent, is:

1. A tool of the character described, including a T-shaped stock, an elongated jacket having the base thereof secured to the

- base of the T-shaped stock, said jacket being open at the top and being formed with stiff spring sides, a sharpening file, and a file receiving clip of U-shaped cross section, the 5 edges of the clip being converged over the file to form a skate guide, and said clip being received within the jacket and forcibly gripped by the spring sides thereof so as to lock the file securely in operative position.
- 10 2. A tool of the character described, including a T-shaped stock, an elongated jacket having the base thereof secured to the head of the T-shaped stock, said jacket being open at the top and at one end thereof and 15 being formed with stiff spring sides, the opposite end of the jacket being provided with a tongue which terminates short of the ends of the sides, a sharpening file, and a sheet metal clip receiving the file and having a 20 U-shaped cross section, the sides of the clip being converged over the file to form a skate guide, and said clip being adapted to be inserted within the jacket with one end thereof in engagement with the before mentioned 25 tongue, the sides of the jacket then forcibly engaging the clip and causing the same to securely grip the file.
3. A tool of the character described, including a T-shaped stock, an elongated jacket having the base thereof secured to the 30 base of the T-shaped stock, said jacket being open at the top thereof and being formed with stiff spring sides, a sharpening file, a file receiving clip of U-shaped cross section, 35 the edges of the clip being converged over
- the file to form a skate guide, and said clip being adapted to be inserted within the jacket with the sides of the jacket forcibly engaging the clip and causing it to securely grip the file, and means for locking the clip 40 in position within the jacket.
4. A tool of the character described, including a T-shaped stock, an elongated jacket having the base thereof secured to the base of the T-shaped stock, said jacket being 45 open at the top and at one end thereof and being formed with stiff spring sides, the opposite end of the jacket being provided with a tongue which carries an inwardly projecting lug at a point adjacent to the base thereof, a sharpening file, and a file receiving clip of U-shaped cross section, the edges of the clip being converged over the file to form a 50 skate guide, said clip being adapted to be inserted within the jacket with one end thereof received under the before mentioned lug of the end tongue, the sides of the jacket then forcibly engaging the clip and causing the same to securely grip the file, and a 55 spring tongue upon the clip for engaging the end of the jacket opposite to that provided with the tongue.
- In testimony whereof we have signed our names to this specification in the presence of two subscribing witnesses.
- JOHN VAN RADEN.
NORMAN VAN RADEN.
